UNITED STATES PATENT OFFICE.

THOMAS A. PEEBLES, OF PITTSBURGH, PENNSYLVANIA, ASSIGNOR TO JOHN M. HOPWOOD, OF DORMONT, PENNSYLVANIA.

FURNACE.

Application filed January 12, 1927. Serial No. 160,691.

This invention relates to furnaces and more particularly to a system of combustion control for furnaces adapted to use different fuels.

8 Furnaces such, for example, as those employed in connection with blast furnaces for the purpose of using blast furnace gas as fuel are subject to wide and sometimes sudden variations in the supply thereof, 10 as a result of variations in the operation of the associated blast furnace or furnaces, and it will be readily understood that the operator of such an arrangement has no control over such a supply. It is customary in 15 times of insufficient supply of such fuel to maintain combustion by feeding an auxiliary fuel into the furnace in place thereof, and this may be done by such a system as that disclosed in my earlier Patent No. 20 1,459,072, granted June 19, 1923, wherein the drop in pressure of the steam generated, resulting from a drop in gas supply, is employed to automatically put into operation mechanism for feeding pulverized coal, or 25 other fuel, into the furnace.

Due to the fact that boilers of this type are normally operated with blast furnace gas only and the powdered coal is used only for the purpose of making up a deficiency in the gas supply, it is not practical to provide draft mechanism, i. e., chimneys, fans or the like, large enough to handle all the products of combustion if the 30 full amount of gas is delivered to the boilers at the same time that a large amount of auxiliary fuel is being supplied thereto, although such a condition has hitherto been possible as a result of a full supply of blast 35 furnace gas being suddenly re-established after a period of small gas supply. In such a case the pressure of the steam generated does not rise with sufficient rapidity to cut off the supply of auxiliary fuel immediately, with the result that both fuels are supplied to the boiler in large quantities at the 40 same time, thus building up a high furnace pressure in the combustion chamber. If the gas burners are of the asperating type, drawing air from the boiler room under the influence of the furnace draft and the asperating effect of the gas, such pressure 45 may blow the flame out through the asperating air openings, causing serious injury to the operator. Aside from this it is very 50 detrimental to any boiler setting to be oper-

ated under such conditions even for a short interval.

An object of this invention is to provide a system of combustion control for furnaces adapted to burn more than a single 60 type of fuel of such construction and arrangement that the rate of feeding of the separate fuels thereto will be regulated in accordance with the furnace capacity.

A further object is to provide a system 65 for supplying auxiliary fuel to a furnace in time of need of such construction and arrangement that such supply will be reduced by the re-establishment of the supply of primary fuel thereto.

A still further object is to provide a system 70 of combustion control for use with furnaces employing blast furnace gas of such character that the supply of auxiliary fuel to the furnace during a period of deficiency 75 in the gas supply thereto will be automatically reduced by the re-establishment of such gas supply.

It is customary to supply a battery of 80 furnaces or boilers with fuel from a single source so that a decrease in the supply of such fuel affects every unit of the battery. It will be apparent that if one or more of such units are cut out under such circumstances, those still in use can still be efficiently operated by the lessened supply of fuel. A still further object of this invention is to provide a system of controlling 85 the flow of fuel to the individual units of a battery of furnaces constructed and arranged to regulate the feeding of fuel to the furnaces in accordance with variations in the supply.

A still further object is to provide a combustion control system of the type set forth 90 which will be relatively simple in construction, and positive and reliable in operation.

These and other objects which will be 100 apparent to those skilled in this particular art are accomplished by means of the present invention which is illustrated in the accompanying drawings in which Figure 1 is a diagrammatic view showing a relative arrangement of parts combined in accordance with one embodiment of this invention and Fig. 2 is a similar view in plan 105 illustrating a further form of control adapted to be employed in connection with a battery of boilers or the like which are subject to a varying supply of fuel.

The particular embodiment of the present invention which has been chosen for the purposes of illustration is shown in Fig. 1 in connection with such a system as that described in my above mentioned patent wherein steam generating boilers are adapted to be normally supplied with gas from an associated blast furnace or furnaces. It will, however, be apparent that the present system has a much wider range of application than the particular type of boiler or the particular type of fuel herein described, and that it is equally applicable to any desired type of furnace or fuel. Like the system disclosed in the patent, the present arrangement includes mechanism for supplying an auxiliary fuel such, for example, as powdered coal to the boiler when the pressure of the generated steam drops below a predetermined point either as a result of the reduction in the available supply of primary fuel, in this case blast furnace gas or because of an unusually large steam demand. The feeding of the auxiliary fuel is continued as long as it is necessary to produce the required amount of steam and if the flow of primary fuel has been low it will be apparent that a sudden resumption in the supply of the latter during feeding of a substantial amount of auxiliary fuel, will produce a highly undesirable pressure in the combustion chamber. In order to prevent this and to automatically reduce the supply of auxiliary fuel as a result of the resumption or increase in the flow of the primary fuel the present invention contemplates the provision of a mechanism which, in this instance, is adapted to be operated by an increase in furnace pressure, for cutting off the supply of auxiliary fuel.

The present invention is illustrated as applied to a system similar to the system of my above mentioned patent and including a furnace 5 having a combustion chamber 6 adapted to be supplied with a combustible mixture of blast furnace gas and air by a burner 7 of any desired type which is connected to a gas main 8 through a supply line 9 and also connected with a fan 10 for supplying air to the burner through the air supply line 11. The gas supply pipe 9 has a valve such as the damper 12 adapted to be operated by a regulator 13 responsive to the pressure in the gas main through the medium of a pressure tap 14. The regulator may be of any desired type but is preferably of the type shown in Patent No. 1,338,923, granted to John M. Hopwood on May 4, 1920. The air line 11 leading to the burner is provided with a similar valve 15 adapted to be operated by a similar regulator 16 responsive to the relative pressures of air and gas flowing to the burner through the medium of the pressure taps 17.

65 A draft outlet 18 leading from the com-

bustion chamber 6 to a stack, fan or the like (not shown) is provided with the usual valve such as the damper 19 adapted to be operated in accordance with the furnace pressure in the combustion chamber by means of a draft regulator 20, similar in construction to the above mentioned regulators, and operated by the furnace pressure through the pressure tap 20'. This regulator is connected to the damper by means of a lost motion connection so that further upward movement of the regulator piston is possible after the damper 19 has been fully opened. As illustrated, this includes a lever 21 adapted to be oscillated by the regulator 20 so as to raise and lower a connecting link 22, the upper end of which is connected to a damper operating lever 23 by a lost motion connection such as the pin and slot connection 24. The opposite end of the damper operating lever 23 is connected to a rod 25 extending downwardly through a bracket 26 and provided with a weight 27 at its lower end. A collar or stop 28 is secured to the rod above the bracket. It will be apparent that, assuming the damper to be closed, upward movement of the regulator enables the weight 27 to rotate the damper to open position. When the damper is fully opened the stop 28 will engage the bracket 26 so that the damper will be held in such position and continued upward movement of the regulator, without affecting the position of the damper, is permitted by the lost motion connection 24 between the operating link and the damper operating lever. Obviously, any type of mechanism can be provided for accomplishing the same function.

The lower end of the piston mechanism of the draft regulator 20 is connected by means of a cable or similar means 29 with one end of a lever 30 pivoted at 31 to a suitable support. The opposite end of the lever 30 is provided with a vertically extending link 32 having a slot 33 adapted to slidably receive a pin 34 secured to a valve controlling lever 35 having a pin and slot connection 36 with a link 37 slidably associated by means of a pin and slot connection 38 with the upper end of a link 39 connected to the frame 40 of a master regulator preferably constructed as described in Letters Patent No. 1,371,243, granted March 15, 1921 to John M. Hopwood. The frame 40 is also connected by a cable 41 or the like to the weighted switch 42 of an automatic starter 43 adapted to make and break the circuit of a motor 44 for driving a pulverizer 45 of any desired type. The upper end of the slotted link 37 is connected with a weight 46 and the opposite end of the valve operating lever 35 is connected by a cable or the like 47 with the weighted operating lever 48 of an auxiliary fuel controlling valve (not shown) adapted to be opened and closed so as to control the

flow of coal from a hopper 49 through a chute 50 to the pulverizer. The particular arrangement of slotted links and levers is similar to that shown in my co-pending application, Serial No. 54,340 filed Sept. 3, 1925. A second cable 51 connects the cable 47 and lever 35 with the weighted arm 52 of an air valve 53 positioned in the air line 54 leading from the fan 10 to the pulverized coal burner 55. It will, of course, be readily understood that any well known way of adjusting the relative proportions of fuel and air may be employed and that the present drawings are purely diagrammatic in character.

It is customary to supply a battery of several furnaces or boilers with fuel from a single source of supply as illustrated in Fig. 2 wherein a multiplicity of boilers 5 are supplied with gas from the single gas main 8. The gas main has the usual damper valve 56 operated by a suitable regulator 57 as is well known in the art.

The gas inlet valves 12 are controlled, as above described, by the regulators 13 in response to variations in the pressure in the gas supply and the regulators are so adjusted that individual boilers or furnaces will be successively cut out, by closing their gas inlet valve 12, as a result of a continuing decrease in the pressure of the gas supply. For example, as the pressure in the gas main 8 falls the furnace at the left in Fig. 2 will have its gas inlet valves checked by the associated regulator so as to reduce somewhat the demand or consumption of fuel and permit the efficient operation of a smaller number of furnaces by the reduced amount of gas. As the gas pressure continues to fall the next furnace will be cut out and so on until the supply of gas in the main is too small to fire any of the boilers, whereupon they will all be cut out and their supply of auxiliary fuels put in full use. Upon return of the gas pressure the respective furnaces are cut back onto the gas main in accordance with the increase in the supply of gas therein.

As the supply of blast furnace gas is reduced the regulator 13 shown in Fig. 1 will check the associated damper 12 so as to reduce the supply of gas to the associated burner and combustion chamber and the consequent unbalancing of the air controlling regulator 16 causes the valve 15 to be correspondingly checked. The reduction in the amount of steam generated, resulting from the reduced combustion, operates the master regulator 40 through a pressure tap 60 connecting the regulator with a steam header 61 as described in the above mentioned Patent No. 1,459,072, so that the movable frame is lowered in such a way as to raise the weighted switch 42 of the automatic starter 65 thus closing the circuit of the motor 44 and

causing the latter to start driving the pulverizer. The lost motion or pin and slot connection 38 between the links 37 and 39 and the provision of the weight 46 attached to the upper end of the link 37 holds the latter stationary during the first part of the downward movement of the lower link until after the closing of the motor circuit and a continued downward movement of the lower link 39 so that the motor and pulverizer are given a sufficient period of time to reach their full speed, even where the steam pressure is dropped rapidly and causing a correspondingly rapid lowering of the regulator frame and the associated links. Continued lowering of the steam pressure and the resulting continued lowering of the frame 40 and link 39 eventually take up the slack in the lost motion connection 38 and pull the link 37 downwardly against the resistance of the associated weight 46. Such lowering of the link 37 lowers the pin and slot connection 36 with the adjacent end of the pivoted auxiliary fuel valve controlling lever 35 so that the latter is oscillated to the left as shown in Fig. 1 under the influence of the weights associated with the respective valve levers 48 and 52, thus causing the associated valves to open and permit the free flow of coal through the pulverizer and to the burner 55 and the flow of air from the fan to the burner. The operation so far described is similar to the operation of the mechanism in Patent No. 1,459,072 and of the various other systems for accomplishing the same purpose.

The present invention contemplates the provision of mechanism for automatically reducing the supply of auxiliary fuel to a boiler in accordance with the resumption of the supply of primary fuel thereto so as to prevent the disadvantages and deterioration resulting from the flow of both fuels into the furnace in large quantities at the same time which occurs when the supply of primary fuel is resumed too rapidly to permit of any immediate and corresponding increase in the pressure of the steam being generated. This is accomplished in the illustrated embodiment of this invention by employing the furnace pressure to control the auxiliary fuel feeding mechanism. This may conveniently be done, as described, by connecting the draft regulator 20, which is operated by the furnace pressure in the combustion chamber, with the mechanism for controlling the supply of auxiliary fuel. In other words, the present invention is arranged so as to limit the furnace pressure to a maximum such as to prevent the building up of too great a pressure of this type with its accompanying disadvantages as above described.

Assuming that the gas supply has been reduced and that the steam pressure has consequently fallen to such an extent as to cause a

supply of powdered coal to be delivered to the combustion chamber 6, and assuming that, during existence of such a condition, the supply of gas is suddenly increased by 5 the resumption of operation of the associated blast furnace, the gas and air valves 12 and 15, respectively, will be opened and an increased supply of gaseous fuel will be admitted to the combustion chamber which is 10 already receiving a substantial amount of pulverized coal. It will be apparent that the furnace pressure in the combustion chamber will immediately rise, and this pressure will excel the draft capacity of the setting if the 15 increase in gas supply is sufficient to render the amount of combined fuels being fed greater than safety or efficiency permits. By means of the pressure tap 20' the regulator 20 will be moved upwardly and the damper 20 19 will be fully opened, while the continued upward movement of the regulator 20, as a result of the excessive furnace pressure, is permitted by the pin and slot connection 24 between the link 22 and the damper operating lever 23. This continued upward movement of the regulator so moves the associated cable 29 as to oscillate the pivoted lever 30 to the right, as shown in Fig. 1, thus raising the connected link 32 sufficiently to take up 25 the lost motion between the slot 33 and the pin 34 of the coal valve operating lever 35 and cause the latter to be oscillated to the right a distance dependent upon the amount of furnace pressure, such oscillation being 30 permitted by the pin and slot connection 36. Obviously, this will so shift the valve connecting cables 47 and 51 as to elevate the weighted valve arms 48 and 52, respectively, and so regulate the associated valves as to 35 40 reduce the rate of feed of the auxiliary and coordinate the supply thereof with the supply of gas. Assuming that the supply of gas is sufficient to cause the complete shutting off of the coal supply, as the steam pressure 45 is built up the master regulator is so operated as to permit lowering of the weighted switch arm 42 and the cutting out of current to the pulverizer motor 44. This movement of the regulator also elevates the associated link 37 50 so that the slack in the lost motion connection 36 is again taken up and the elements assume the position shown in Fig. 1. The rise of the furnace pressure in the combustion chamber to normal causes the associated regulator 20 to lower the damper connecting link 22 to the position shown in Fig. 1 where its further movement will cause a variation in the position of the damper in accordance with variations in the furnace pressure and 55 such lowering of the regulator 20 returns the associated lever 30 and link 32 to the position shown in Fig. 1, but it will be apparent that such movement will have no effect upon the valve operating lever 35, due to the fact that 60 the regulator 40 and link 37 have previously 65 assumed such a position as to hold the lever in valve closing position, as illustrated. Obviously, the desired result can be effected by fuel controls operated by conditions other than the particular one described, i. e., furnace pressure. The principal feature is such a control of the fuel supply as to prevent such supply from ever being greater than can be safely accommodated by the particular draft capacity of any particular furnace 70 75 in operation.

It will be apparent to those skilled in the art that the present invention can be successfully employed with many different types of furnaces using a wide variety of 80 fuels and that various arrangements other than that described can be used.

It will also be apparent that various changes, additions, substitutions and omissions can be made in the particular arrangement of elements described, all without departing from the spirit of this invention or the scope of the appended claims. What I claim as new and desire to secure by Letters Patent is:

1. The combination with a furnace of means for supplying fuel thereto from a source of variable supply, means for supplying fuel thereto from a second source and means for regulating the operation of one 95 of said fuel-supply means to prevent the furnace pressure from exceeding a predetermined maximum.
2. The combination with a furnace adapted to burn a primary fuel of mechanism for 100 supplying an auxiliary fuel thereto and means for controlling the operation of said mechanism in accordance with the furnace pressure.
3. The combination with a steam generating boiler adapted to burn a primary fuel of means for supplying an auxiliary fuel thereto in response to a decrease in steam pressure and means responsive to an increase in the furnace pressure for controlling the supply 110 of auxiliary fuel.
4. The combination with a steam generating boiler adapted to burn a primary fuel of means for supplying an auxiliary fuel to said boiler in response to a decrease in steam 115 pressure and means for controlling the supply of auxiliary fuel to said boiler in accordance with the pressure in the combustion chamber thereof.
5. The combination in a furnace of mechanism for supplying a primary fuel thereto, mechanism for introducing an auxiliary fuel thereto and means responsive to the furnace pressure for coordinating the operation of 120 said mechanisms.
6. The combination with a furnace adapted to burn blast furnace gas of means for supplying an auxiliary fuel thereto when the 125

supply of blast furnace gas is insufficient and means responsive to the furnace pressure for controlling the supply of auxiliary fuel.

7. The combination with a furnace of means for supplying a primary fuel thereto, means for supplying an auxiliary fuel thereto, pressure responsive means for operating said auxiliary fuel supply and mechanism operated by the furnace pressure for preventing the operation of said pressure responsive means.

8. The combination with a steam generating boiler of means for supplying blast furnace gas thereto, mechanism for supplying an auxiliary fuel thereto in response to a decrease in steam pressure, draft regulating mechanism responsive to the furnace pressure and means operated by said draft regulator for controlling the supply of auxiliary fuel.

20 9. The combination with a battery of furnaces of means for supplying fuel thereto from a source of variable supply and means for shutting off one or more of said furnaces in accordance with the reduction in the supply of said fuel.

10. The combination with a battery of furnaces adapted to burn blast furnace gas of means for supplying such gas thereto and means for progressively shutting off said supply from successive furnaces in accordance with a reduction in the supply of said gas.

11. The combination with a battery of furnaces adapted to burn blast furnace gas of a gas main, connections between said main and each of said furnaces, a valve in each of said connections and a regulator associated with each valve and responsive to

variations in the pressure in said gas main 40 for progressively closing successive valves in proportion to a reduction in the gas pressure in said main.

12. The combination with a steam generating boiler adapted to burn primary fuel 45 of means for supplying an auxiliary fuel thereto and means for controlling the supply of auxiliary fuel in accordance with the draft capacity of the furnace.

13. The combination with a steam generating boiler adapted to burn primary fuel 50 of pressure responsive means for supplying an auxiliary fuel thereto and means for limiting the supply of auxiliary fuel in accordance with the draft capacity of the furnace. 55

14. The combination with a furnace of means for supplying separate fuels thereto and pressure responsive mechanism for limiting the supply of one of said fuels.

15. The combination with a steam generating boiler of means for supplying separate fuels thereto and pressure responsive mechanism independent of the pressure of steam generated for controlling the supply of one 60 of said fuels. 65

16. The combination with a steam generating furnace of a main burner associated with a source of variable fuel supply, an auxiliary burner, means for supplying fuel to said auxiliary burner in accordance with 70 the steam pressure, and means operated by an increase in the supply of fuel to said main burner for reducing the supply of fuel to said auxiliary burner.

In testimony whereof, I have hereunto 75 subscribed my name this 11th day of January, 1927.

THOMAS A. PEEBLES.
